(57) **CLAIM**

The ornamental design for a container with handle, as shown and described.

DESCRIPTION

FIG. 1 is a front, perspective view of a container with handle showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is a front, perspective view of the container with handle of FIG. 1 with additional unclaimed subject matter shown in broken lines;

FIG. 9 is a front view thereof;

FIG. 10 is a rear view thereof;

FIG. 11 is a right side view thereof;

FIG. 12 is a left side view thereof;

FIG. 13 is a top view thereof; and

FIG. 14 is a bottom view thereof.

FIG. 15 is a front, perspective view of the container with handle of FIG. 1 with additional unclaimed subject matter shown in broken lines;

FIG. 16 is a front view thereof;

FIG. 17 is a rear view thereof;

FIG. 18 is a right side view thereof;

FIG. 19 is a left side view thereof;

FIG. 20 is a top view thereof; and,

FIG. 21 is a bottom view thereof.

The features shown in broken lines are portions of the container with handle or environmental subject matter to the container with handle forming no part of the claimed design. Any internal surfaces of the container with handle that are impeded from view by broken line showings are not claimed.

1 Claim, 21 Drawing Sheets
